UNITED STATES PATENT OFFICE.

HERBERT W. SMITH, OF COON RAPIDS, IOWA.

WINDOW-SHADE BRACKET.

1,281,441.

Specification of Letters Patent. Patented June 26, 1917.

Application filed August 30, 1916. Serial No. 117,685.

To all whom it may concern:

Be it known that I, HERBERT W. SMITH, a citizen of the United States, residing at Coon Rapids, in the county of Carroll and 5 State of Iowa, have invented certain new and useful Improvements in Window-Shade Brackets; and I do hereby declare the following to be a full, clear, and exact description of the invention, such as will enable others skilled in the art to which it 10 appertains to make and use the same.

This invention relates to improvements in window shade brackets.

The object of this invention is to provide 15 a window shade bracket which may be easily and quickly applied to and removed from a window frame without the use of fastening means and thereby eliminating any fear of marring the wood work of the sash frame.

20 A further object of this invention is to provide a window shade bracket which comprises in its construction a pair of spaced members pivoted together and a window shade supporting arm carried by the spaced 25 members to permit the same to be readily and quickly clamped in the groove of a window sash frame.

A further object of this invention is to provide 30 a window bracket of this construction, which will be simple, practical, and comparatively inexpensive in construction, and one that can be manufactured and sold at a comparatively low cost.

With these and other objects in view the 35 invention consists in the novel combination and arrangement of parts hereinafter more fully described and set forth in the claims hereto appended.

In the drawings:

40 Figure 1 is a perspective view of my window shade brace bracket made in accordance with this invention,

Fig. 2 is a side elevation showing the 45 clamping members in position, to be placed between the parting strips of the window frame,

Fig. 3 is a rear elevation, partly broken away to disclose the pivoted side members, and

50 Fig. 4 is a sectional view taken on the line 4—4 of Fig. 2,

Fig. 5 is a perspective view illustrating the device applied to a window frame.

Referring more particularly to the drawings, the numerals 1 and 2 designate the 55 attaching members which are constructed of

flat sheet metal or any other suitable material, and have their upper and lower ends bent or rolled back upon themselves to form barrels 3. The members 1 and 2 are arranged in spaced relation to one another and are pivotally connected together at their upper ends by the U-shaped member 4 which has its legs journaled in the barrels 3 in the upper ends of the members 1 and 2. 60 65

An arm 5 formed of metal or any other suitable material and preferably rectangular in cross section is provided on one face near one end with the spaced pins 6 and 7, which pins are journaled in the lower rolled 70 ends 3, of the members 1 and 2 permitting the members to be collapsed to be positioned in the groove of the window frame and by forcing the arm 5 downwardly the same will seek its normal position and firmly clamp 75 the members 1 and 2 into engagement with the walls of the grooves in the window sash construction.

The arm 5 is provided at its outer end with an annular guide ring 8, which is 80 rigidly connected to the end of the arm and has one wall spaced therefrom, the wall spaced from the arm 5 is provided centrally with an opening 9, through which is adapted to extend the screw threaded bolt 10, the 85 purpose of which will be hereinafter more fully described.

A supporting arm 11 is slidably mounted through the guide ring 8, and is provided with an elongated longitudinally extending 90 opening 12 which is adapted to have the bolt 10 pass therethrough for holding this arm in adjusted position within the ring 8. A nut 13 is fitted on the inner end of the bolt 10 for holding this arm in adjusted 95 position with relation to the arm 5. The inner end of the arm 11 is turned outwardly as at 14, to prevent the same from being entirely withdrawn from the ring 8. The outer end of the arm 11 is bent angularly 100 as at 15 and has rigidly secured to its outer end the guide ring 16, and extending centrally through the guide ring is the bolt 17 which is provided with a nut 18, the purpose of which will be hereinafter more fully 105 described.

A shade supporting arm 19 is substantially L-shaped and has one of its arms provided with elongated openings 20, which arm extends through the ring 16 and its end 110 turned outwardly to prevent the same from being entirely withdrawn from the ring 16.

The shorter arm 21 of the L-shaped member 19 is provided with a shade or pintle bearing receiving opening 22 adapted to receive one end of the window shade therein supporting the same to a window.

It being understood that there are two of these devices used and the one shown is for the right side of the window and the one for the opposite side of the window will be identical in construction only applied to the reverse side of the bar 5.

In use:

The members 1 and 2 are forced downwardly toward the outer end of the bar 5, and are placed in the groove in the window sash and the bar 5 is forced downwardly thereby spacing the members 1 and 2 and firmly clamping the same between the stops 4 of the outer sash to firmly clamp the same in position, the arms 19 and 12 are adjusted to position the same in proper proportion to the window shade used, and the shade is then placed in position, and the device is ready for use.

What is claimed is:

1. A window shade bracket comprising a pair of spaced attaching members, means pivotally connecting the upper ends of the members together, and a shade supporting arm pivotally connecting the lower ends of the members together, said means and arm permitting the members to collapse one toward the other to permit the same to be placed between the parting strips of the window frame.

2. A window shade bracket comprising a pair of relatively spaced side members, a U-shaped member journaled in the upper ends of the side members, an arm having one end journaled to the lower end of said members, a ring on the outer end of the arm, a supporting arm slidably and adjustably mounted in the ring, and a shade supporting arm adjustably associated with the outer end of the supporting arm.

3. A window shade bracket comprising a pair of flat spaced members having their upper and lower ends rolled to provide bar-

rels, a U-shaped member having its arms journaled in the barrels in the upper ends 50 of the members, a bar, pins arranged on one face of the bar near one end thereof, said pins being in spaced relation and adapted to be journaled in the barrels at the lower ends of the members, a ring on 55 the outer end of the bar, a supporting arm slidably mounted in the ring, and a bracket supporting arm adjustably connected to the outer end of the supporting arms.

4. A window shade bracket comprising a 60 pair of spaced members having barrels at the upper and lower ends, a U-shaped member journaled in the upper barrels of the members, a bar, pins arranged on one face of the bar at spaced distances apart, said 65 pins journaled in the barrels at the lower ends of the members to permit the same to be collapsed, a guide ring at the outer end of the bar, a supporting arm slidably mounted in the guide ring, means extending 70 through the guide ring and arm for holding the same in an adjusted position, the outer end of said supporting arm bent angularly and provided with a guide ring, an 75 L-shaped shade supporting arm slidably mounted in the last named guide ring and means for holding the last named arm in adjusted position with relation to the supporting arm.

5. A window shade holder comprising a 80 pair of relatively spaced attaching members, means pivotally connecting the upper ends of the members together, an arm pivotally associated with the lower end of the members, and an adjustable shade supporting 85 arm connected with the outer end of the first named arm, said shade supporting arm of the first named arm holding the attaching members in vertical parallel attaching position.

In testimony whereof I affix my signature in presence of two witnesses.

HERBERT W. SMITH.
